SYRINGE FOR HYPODERMIC INJECTION
Samuel James Everett, London, England, assignor to
Lapis Engineering Company Limited
Filed Dec. 5, 1961, Ser. No. 157,105
4 Claims. (Cl. 128—218)

This invention relates to hypodermic syringes.

The nature of the invention will otherwise be clear from the appended claims when read in the light of the following description of the particular and at present preferred embodiment thereof which is illustrated in the accompanying drawings. In these drawings:

FIGURE 1 is a longitudinal section through a hypodermic syringe constructed in accordance with the invention;

FIGURE 2 is a section on the line AA of FIGURE 1 on a smaller scale;

FIGURE 3 is an outside view of the syringe on an even smaller scale;

FIGURES 4 and 5 are plan and side views of a needle 12 and bag 16 used in the syringe shown in FIGURES 1 to 3;

FIGURE 6 is an outside view of a loading assembly for inserting the needle 12 and bag 16 shown in FIGURES 4 and 5, into the syringe shown in FIGURES 1 to 3;

FIGURE 7 is an end view of the assembly shown in FIGURE 6; and

FIGURE 8 is a half sectional elevation of a modified form of plunger for use in the syringe illustrated in FIGURES 1 to 3.

The hypodermic syringe comprises a cylindrical glass barrel or casing 10 containing an operating plunger 11 which makes sliding fluid-tight engagement with the wall of the barrel. A needle 12, consisting of a cannula 14 and a hub 15 secured about the rear end of the cannula, is removably mounted on the front end of the casing 10, and the lumen of the needle communicates with the interior of a bag 16 made of pliable sheet material. The bag and needle are located in an aperture in a bushing or gland 17 of elastomeric material which is sealed to the wall of the barrel 10, clamping means 18 being provided to deform the gland to make a fluid tight seal around the bag and the needle.

The operating plunger 11 has a stem 19 of reduced diameter which extends rearwardly through a clearance hole in an end cover plate 20 removably attached to the rear end of the barrel, the stem terminating in an enlarged end portion 21. The plunger has a passage 25 through it which is normally closed by a spring loaded ball valve 26. The open end of the passage 25 at the front end of the plunger is protected by a cap 27 screwed into the plunger, the rear face of the cap being spaced from the front face of the plunger to allow the flow of fluid from the interior of the barrel to the passage 25.

The above mentioned gland 17 is contained by a cylindrical metal sleeve 30 mounted on the front end of the barrel 10. This sleeve houses a pair of thin metal discs 31, 32 which are clamped against projecting annular shoulders, formed on the inside of the sleeve, by upsetting the wall of the sleeve adjacent the shoulders. Projecting forwardly from the front disc 31 is a bayonet socket 33 concentric with the disc. Located in the space between the discs is a pair of part cylindrical metal collets 34 whose outer surfaces fit closely against the inner surface of the sleeve 30, and whose end faces are spaced a short distance from the respective discs.

The gland 17 is formed by injecting a mass of silicone rubber into the space between discs 31, 32 and this material fills the gaps between the collets 34 and the respective discs, and also fills the space between the collets except for a cylindrical aperture 35, the discs 31, 32 being

2

formed with correspondingly shaped apertures so as not to obstruct gland aperture 35. The mass of silicone rubber which forms the gland 17 continues integrally into the space immediately behind the rear disc 32 so as to form a yielding end wall 36 to the casing 10. This wall is dished forwardly to leave a frusto conical space communicating at its narrowest part with the gland aperture 35.

The silicone rubber which forms the gland 17 and the end wall 36 is bonded to the glass barrel 10 and to the sleeve 30 and so that the sleeve is secured to the barrel without any direct rigid connection.

The above mentioned clamping means 18 comprise a clamping ring 40 fitting loosely over the outside of sleeve 30. The ring has a pair of inwardly projecting pegs 41 and 42 which pass through holes in the sleeve 30 and bear against the collets 34. One peg, 42, is formed as a screw extending through a threaded hole in the clamping ring 40 and carries at its outer end a knurled finger wheel 43 facilitating rotation of the peg 42 to vary the inward pressure exerted on the collets by the pegs.

The bag 16 is formed by welding together two layers of thin polyethylene sheet material, and in consequence is very pliable. The bag is so dimensioned that when it is fully expanded it will fill the cross section of the barrel 10, and in its flattened condition is wider than the aperture 35 through which it is passed when first inserted into the barrel. In order to facilitate the insertion of the bag into the barrel of the syringe through gland aperture 35, it is first positioned over the hub 15, as shown in FIGURES 4 and 5. The bag and needle together are then pushed into a sheath 50, shown in FIGURES 6 and 7, which is formed as an open ended tube split longitudinally. The sheath is of stiff but springy material such as celluloid rigid P.V.C. or the like, and is of a size to pass through the gland aperture 35.

The bag is folded lengthwise to fit inside the sheath, and is resiliently gripped over the hub by the sheath which is so dimensioned that it must be expanded slightly to fit over the hub. A radially projecting pin 15A on the hub pierces the wall of the bag and extends through the slot in the sheath. This peg is adapted to be engaged in the slot of the socket 33, as will be explained below.

Preferably, the outside of the bag is treated with a suitable lubricant such as a silicone oil to prevent its sticking to the glass barrel 10 during operation of the syringe.

The sheath and its contents may be housed in a sealed container (not shown) and the whole sterilised ready for use.

To load the bag and needle into the barrel, the plunger 11 is first drawn outwardly to its rearmost position and the rear end of the sheath (the right hand end as seen in FIGURE 4), is inserted through the socket 33 and the gland aperture 35.

The peg 15A on the needle hub 15 is guided into the axially extending part of the bayonet slot in the socket 33, and then by rotating the sheath, into the circumferential part of the slot. The sheath is then drawn forwardly over the bag and needle and out of the gland aperture, leaving the bag and needle in their desired positions in the syringe. It will be noted that by use of the loading assembly described above, the bag and needle are positioned in the syringe without being touched by hand so that their sterility is preserved.

The screwed peg 42 is tightened so that the two pegs 41 and 42 press the collets 34 inwardly to deform the gland 17 and collapse the aperture 35 about the bag and the hub, the gland now forming a fluid tight seal about the hub.

As a preliminary to filling the syringe with medicament or other fluid, the plunger 11 is moved inwardly in the barrel so that the bag 16 is collapsed between

the yielding end wall 36 and the plunger 11. The bag is forced by the plunger into the frusto-conical recess defined by wall 36 and any air in the bag is expelled through the lumen of the cannula 14. The size and shape of the plunger is however such that it cannot fill the space in wall 36 and so the crushing force which can be applied to the bag is limited. This, and the yielding nature of end wall 36 prevent the bag from being torn.

As the plunger moves inwardly, air contained in the space within the barrel not occupied by the bag 16 passes outwardly through the passage 25 against the action of the spring loaded ball valve 26, and in this way substantially all the air in this space is expelled. The cap 27 on the front of the plunger prevents the bag from blocking the passage 25 during this process.

The sharp end of the cannula 14 is now dipped into a supply of medicament to be injected, and the plunger is drawn outwardly. During this outward movement the valve 26 is held closed by its spring assisted by the resultant pressure difference between the interior and the exterior of the barrel. As the pressure within the casing is reduced, the bag 16 is caused to expand and draw in fluid through the lumen of the cannula 14.

The bag is filled in this way to the desired extent, and FIGURE 3 shows the syringe with the bag completely filled and the syringe ready for an injection. When the plunger is pushed inwardly it presses on the bag so as to collapse it and expel the medicament through the lumen of the needle.

When the injection is completed the clamp 18 is slackened by unscrewing the peg 42 thus releasing the grip exerted on the bag and the needle by the gland 17. The hub is rotated and pulled forwardly out of the bayonet socket 33, bringing the bag with it. The needle and bag are either discarded or re-sterilised for future use, and the syringe may be loaded with a fresh bag and needle for another injection operation.

Since the arrangement is such that only the bag and needle come into contact with the medicament or with the patient, there is no need for any other part of the syringe to be sterilised after a single use.

Another feature of the syringe is its ability to deliver accurately metered dosages, even of a few cubic centimetres. This derives from the fact that the bag is emptied progressively from its rear end to its front end by the plunger, so that the displacement of the plunger corresponds with the amount of fluid contained in the bag. This progressive emptying would not be achieved if the space within the barrel not filled by the bag was not exhausted of air prior to filling the bag. The presence of air in this space would also prevent the plunger from being pushed fully forward into the barrel.

The syringe can of course be used for drawing off fluid from a patient. In this case the filling of the bag takes place while the needle is inserted in the appropriate part of the patient. The sample can then be ejected through the needle by inward movement of the plunger. Alternatively, without emptying the bag, the clamp 18 is released and the needle and bag are pulled out of the barrel through the gland aperture 35 and the socket 33. It is found that the bag can be removed in this way without any substantial loss of the fluid in the bag, in spite of the comparatively small cross-section of the gland opening through which the bag must pass.

The syringe is described above as employing a needle in which a needle mount constituted by the hub 15 is secured about the end of a cannula 14, this mount being clamped in the flexible gland 17.

Other forms of needle mount can of course be used in conjunction with the syringe. For example, a hollow needle mount whose front portion is formed as the male part of a Luer lock coupling can be positioned in the gland the said front portion forming a nipple to which can be coupled a Luer socket secured about the rear end of a cannula. In this case the loading assembly

illustrated in FIGURES 6 and 7 is modified by the substitution for the needle 12 of the hollow needle mount.

It will be appreciated that a flexible gland such as that described above can equally well be used in syringes in which the medicament comes into direct contact with the walls of the barrel or casing.

Variation and modifications in the construction and operation of the syringe specifically described herein will of course be possible within the scope of the appended claims.

According to a particular modification, the passage 25, instead of emerging at the rear end of the enlarged portion of the plunger, extends through the stem 19 and opens on to the rear face of the enlargement 21 at the rear end of the stem. The ball valve 26 is dispensed with and the passage is closed when required by the user's thumb.

Another form of plunger which can be used with the syringe shown in FIGURES 1 to 3 is illustrated in FIGURE 8. This plunger 111 has a stem 119 secured at its rear end, and its cylindrical surface is helically knurled so that the surface cannot form a fluid tight seal against the wall of the barrel 10. The plunger is formed with an annular recess 112 housing a washer 120 which is of flexible material, for example, silicone rubber. The diameter of the washer is larger than that of the barrel 10 so that when the plunger is inserted in the rear end of the barrel the periphery of the washer engages the wall of the barrel. In operation the washer 120 acts as a cup leather, that is: when the plunger is moved rearwardly, the washer is pressed against the front face of the recess 112 and forms a fluid tight seal with the wall of the barrel 10; when the plunger is moved forwardly, the washer flexes to allow the passage of air between the periphery of the washer and the wall of the barrel.

I claim:

1. In a hypodermic syringe a casing having at its forward end an end wall defining an aperture for removably receiving a collapsible bag, said aperture being of reduced cross-sectional size relative to the interior of the casing, the end wall at said forward end of the casing constituting a bushing of elastic material sealed to a side wall of the casing, a plunger extending slidably into the casing from the rear end thereof, a collapsible bag with a needle hub for holding fluid contents of the syringe, said bag in laterally collapsed condition being removably insertable through said aperture into said casing, means for sealing said bag in said aperture with the interior of the bag opening through said aperture to the exterior of the casing, said means comprising clamping means operable to deform said bushing to collapse the aperture, thereby forming a fluid-tight seal around the bag, rearward movement of said plunger operating to reduce air pressure within said casing and causing said bag to fill with fluid passing through said aperture, whereby said bag is expanded to fill the interior of the casing over its full cross section.

2. A syringe in accordance with claim 1 in which rigid clamping members are embedded in the material of the bushing so as partially to surround the said aperture, and the clamping means are operable to press those members towards each other to collapse the aperture.

3. In a hypodermic syringe including a chamber for removably receiving a collapsible bag containing a treatment fluid, a barrel wall, an apertured end wall made of flexible material fixedly sealed to one end of said barrel wall and a movable end wall slidable in said barrel wall in fluid tight engagement therewith, said walls defining said chamber, a collapsible bag with a needle hub removably fitted into said chamber with one end extending into said aperture in sealing engagement with the wall defining the aperture, said movable end wall constituting the face of a plunger whereby upon movement of the plunger toward said apertured end wall the bag is col-

lapsed, the flexibility of said apertured end wall protecting the bag against being torn.

4. A syringe in accordance with claim 3 in which the fixed end wall is dished forwardly to form a space into which the bag is pressed by the plunger, the plunger face being flat so that it cannot fill the space, whereby the extent to which the bag can be collapsed by the plunger is limited.
